FIG. 4.

FIG. 5.

UNITED STATES PATENT OFFICE.

GEORGE D. HECK, OF PRINCE BAY, NEW YORK, ASSIGNOR TO THE S. S. WHITE DENTAL MANUFACTURING COMPANY, OF PHILADELPHIA, PENNSYLVANIA, A CORPORATION OF PENNSYLVANIA.

BURR HOLDER.

Application filed November 23, 1922. Serial No. 602,697.

To all whom it may concern:

Be it known that I, GEORGE D. HECK, a citizen of the United States, and a resident of Prince Bay, in the county of Richmond, 5 State of New York, have invented certain new and useful Improvements in Burr Holders, of which the following is a specification, reference being had to the accompanying drawings.

10 My invention relates particularly to that class of devices that are arranged to contain a plurality of tools such as drills, burrs, or other such implements, and which are commonly known as tool-racks, stands, blocks 15 or holders; and is especially directed to a container or holder which is not only adapted to carry such tools, but which may be so converted as to be employed to display the tools therein contained for convenient selection, and from which they may be withdrawn and replaced.

20 The principal objects of my invention are to provide a tool-holder comprising a container, having a closure affording means to prevent the accidental displacement of the 25 tools from their respective recesses or sockets in said container when employed as a closure therefor, and which when removed may afford a support upon which the tool 30 container comprising a rack may be conveniently held so inclined as to afford easy access to the tools therein contained.

35 Other objects of my invention are to provide a tool-holder with a closure formed of articulated sections arranged to be folded, and respectively forming a base and a strut by which the container comprising the tool-rack may be supported in inclined relation to the base, and having cooperative means 40 whereby said tool-rack may be engaged with the base and strut as to prevent accidental tipping or tilting from its inclined position.

45 My invention comprehends a tool-holder wherein the tools are so disposed that they may be relatively close together, yet afford easy access for withdrawal by the operator.

50 Specifically stated, the form of my invention as hereinafter described comprises a tool-holder providing a rack having a plurality of sockets arranged to receive the shanks of tools and support them in readily removable angular relation thereto, and having a removable closure arranged to engage the tools therein, to prevent accidental displacement from their respective sockets, said

closure being formed of sections pivoted together, the shorter section being arranged to fold back upon the longer section and to be engaged by a tongue forming a clip extended from the bottom wall of said holder, 60 and the longer section having its end wall recessed and provided with a lip arranged to engage the edge of said tool-holder to prevent its displacement therefrom, said lip being also arranged to engage suitably 65 provided retaining lugs on the end of said rack when the closure is employed to close said holder.

70 My invention also includes all of the various novel features of construction and arrangement as hereinafter more definitely specified.

75 In the accompanying drawings Figure 1 is a plan view of a burr-holder constructed in accordance with my invention, a fragment being broken away for convenience of illustration; Fig. 2 is a side elevational view of the burr-holder shown in Fig. 1, a fragment being broken away for convenience of illustration; Fig. 3 is an end elevational view of said burr-holder as viewed from the right hand end of Figs. 1 and 2; Fig. 4 is a central longitudinal sectional view of the burr-holder, shown with the closure removed and folded to support the tool- 80 carrying body or tool-rack; and Fig. 5 is a front elevational view of the closure per se, as shown in Fig. 4, folded to support the tool-carrying body.

85 In said figures the tool-carrying body or tool-rack 1, is provided with a closure comprising the articulated sections 2 and 3, which are provided with the hinge pintles 4, about which said sections may relatively turn. Said closure sections are respectively 90 provided with punched projections 5 and 6, extending outwardly and forming cups or depressions on the inner surface of the side walls thereof, so disposed that the projections 5, may be caused to register with and 95 fit into the cups formed by the projections 6, to hold the sections 2 and 3, in relatively inclined position to respectively form a base and a strut upon which the tool-carrying body 1, may be supported, as shown in Fig. 4. 105

110 The tool-carrying body 1, preferably comprises a shallow rectangular pan having a bottom and side and end walls, the free edge of which is turned over to provide the cylindriform bead 9, which serves to retain a

plurality of strips of sheet metal 10, folded in the form of three-sided channels and having their respective lateral webs 12, provided with semi-cylindrical recesses 13, disposed in inclined relation to the plane of the transverse webs 14, which connect the lateral webs of said channels, and which form the floor of the tool-carrying body or rack. When the channel members are disposed side by side in the pan the semi-cylindrical recesses in the adjacent lateral webs of the channels, register and form substantially cylindrical sockets in the floor formed by the transverse webs 14, as shown in Fig. 1, arranged to receive the shanks 15, of the burrs 16, and to hold them in such inclined relation to the floor of the tool-carrying body that when said body is supported in inclined position by the folded closure, as shown in Fig. 4, the burrs will be disposed with their axes extended vertical and in position to be conveniently selected and withdrawn or replaced.

The end wall 17, of the closure section 3 forming the strut, has its central portion 18, projected and inclined slightly at an angle to said end wall proper, for convenient engagement with the tongue 19, which is punched from the bottom of the pan forming the tool-carrying body 1. The end wall 20, of the closure section 2, forming the base of the tool body support, terminates in a curled lip 21, which is arranged to embrace the cylindriform edge of the body 1, along its lower end, when supported by the closure. When said tool-carrying body is thus engaged by the lip 21, and the tongue 19, engaged with the inclined portion 18, of the end wall of the strut, the tool-carrying body 1, is rigidly held inclined and prevented from any possible tipping, tilting or accidental displacement from the stand or easel formed by the closure.

The tool-carrying body 1, has its end wall 22, provided with lugs 23, punched therefrom beneath which the lip 21, forming the edge of the end wall 20, of the closure section 2, may be engaged when the closure sections 2 and 3, are extended in a plane to form the closure adapted to cover the tool-carrying body, as shown in Figs. 1, 2 and 3.

As shown in Fig. 2, the side walls of the tool-carrying body 1, are provided with a roughened area 25, preferably by the formation of a plurality of minute projections, to afford an easy grip to be grasped by the thumb and finger when it is desired to remove the closure, and the side walls of the closure are provided with cut-out substantially semicircular recesses 26, at the region of said roughened area 25, to facilitate the engagement of said roughened area by the thumb and finger of the operator.

The bottom of the tool-carrying body 1,

is provided with embossed projections 29, preferably arranged in triangular relation to form supporting feet for the tool-holder when the closure is in place to form a cover, as shown in Figs. 1, 2 and 3; and the base forming section 2, of said closure is provided with embossed projections 30, similarly arranged to form supporting feet for the closure when folded to support the tool-carrying body.

As best shown in Fig. 2, the closure is adapted to retain the burrs 16, in their respective sockets, so as to prevent them being displaced in transportation or in the handling of the burr-holder, and may be conveniently removed and folded to form a stand or easel upon which the burr-carrying body may be conveniently supported, as shown in Fig. 4, when not supported upon its feet formed by the projections 29.

I do not desire to limit my invention to the precise details of construction and arrangement as herein set forth, as it is obvious that various modifications may be made therein without departing from the essential features of my invention as defined in the appended claims.

Having thus described my invention, I claim:

1. A tool-holder having a body forming a rack provided with a plurality of inclined tool-receivers, and means arranged to support said body so inclined that the tools in said receivers will assume a substantially vertical position.

2. A tool-holder comprising a body forming a rack provided with a plurality of inclined tool-receivers, and a closure therefor arranged to support said body so inclined that the tools in said receivers will assume a substantially vertical position.

3. A tool-holder comprising a body forming a rack provided with a plurality of inclined tool-receivers, and a closure therefor comprising articulated sections arranged to be folded to provide a support for said body so inclined that the tools in said receivers will assume a substantially vertical position.

4. A tool-holder comprising a body forming a rack provided with a plurality of inclined tool-receivers, and a closure therefor arranged to retain the tools in said receivers, said closure being formed of relatively movable sections respectively forming a base and a strut arranged to support said body so inclined that the tools in said receivers will assume a position convenient for selection and withdrawal.

5. A tool-holder comprising a body forming a rack provided with a plurality of inclined tool-supports, and a closure therefor so related to said body as to prevent accidental displacement of said tools from said supports, said closure comprising relatively

movable sections respectively forming a base and a strut arranged to support said body so inclined that the tools in said supports will assume a substantially vertical position, and means arranged to rigidly engage said body therewith.

6. A tool-holder having a body forming a rack provided with a plurality of inclined tool-receiving sockets, and a closure therefor formed of relatively movable sections respectively arranged to provide a base and a strut for supporting said body inclined, said body being provided with means arranged to resistively engage the section forming the

15 strut.

7. A tool-holder comprising a body forming a rack provided with a plurality of inclined tool-receiving sockets, and a closure therefor arranged to embrace said body and 20 to retain the tools in their respective sockets, said closure being formed of relatively mov-

able sections arranged to be angularly disposed with respect to each other and respectively forming a base and a strut for supporting said body so inclined that the tools 25 in said sockets will assume a substantially vertical position; the strut section having means arranged to be engaged by the body, means projecting from said body and arranged to cooperate with said strut section 30 to rigidly hold said body and said strut together, and means on said base section arranged to engage said body to prevent its accidental displacement therefrom.

In witness whereof, I have hereunto set 35 my hand this 3rd day of November, A. D. 1922.

GEORGE D. HECK.
